UNITED STATES PATENT OFFICE.

GEORGE H. BLISS, OF BOSTON, MASSACHUSETTS, ASSIGNOR TO A. G. BRADISH & SON, INC., OF BOSTON, MASSACHUSETTS, A CORPORATION OF MASSACHUSETTS.

COVER-SECURING HOOP.

1,378,649.

Specification of Letters Patent. Patented May 17, 1921.

Application filed May 29, 1920. Serial No. 385,242.

To all whom it may concern:

Be it known that I, GEORGE H. BLISS, a citizen of the United States, residing at Boston, in the county of Suffolk and State of 5 Massachusetts, have invented new and useful Improvements in Cover-Securing Hoops, of which the following is a specification.

This invention relates to means for detachably securing a cover to the upper end 10 of a receptacle, such as a butter tub, and is embodied in a hoop which is formed from an elongated sheet metal strip, and includes a lower portion or zone, adapted to embrace, and be attached to the upper end of the receptacle, and a rolled inwardly projecting 15 bead, forming a downhold, adapted to bear on the marginal portion of the receptacle cover, the hoop being of the improved construction hereinafter described and claimed.

20 Of the accompanying drawings forming a part of this specification,—

Figure 1 is a perspective view of a partially completed hoop embodying the invention.

25 Fig. 2 is a section on line 2—2 of Fig. 1, showing the hoop completed.

Fig. 3 is a fragmentary sectional view, showing the hoop engaged with a receptacle and its cover.

30 Fig. 4 is an edge view of a portion of the hoop in the condition shown by Fig. 1.

Fig. 5 is an edge view of a portion of the hoop in the condition shown by Fig. 2.

Fig. 6 is a side view of the strip or blank 35 from which the hoop is made, the central portion being broken away.

Fig. 7 is a fragmentary perspective view, showing a modification.

The same reference characters indicate the 40 same parts in all of the figures.

In carrying out my invention, I form from sheet steel, or other suitable sheet metal, an elongated strip or blank, substantially as shown by Fig. 6, and convert the 45 same by suitable operations, into a cover-securing hoop, a sectional view of which is shown by Fig. 2. Joint-forming end portions 12 and 13, of the strip, are overlapped and united as by rivets 14, to form a joint 50 which is narrower than the maximum width of the strip. As shown by Figs. 2, 4, 5 and 6, the end portion 12 is relatively narrow, and the end portion 13 has the full width of the strip. As shown by Fig. 7, both end 55 portions are narrower than the body of the

strip, a relatively narrow portion 13^a being substituted for the portion 13, the arrangement being such that, in either case the joint is narrower than the maximum width of the hoop, and the hoop has two opposed edge 60 portions 15, which are located above the joint, and are separated by a crevice.

The lower edge portion of the hoop below the dotted line 16, constitutes a continuous receptacle embracing lower zone which includes the said joint. The upper edge portion of the hoop, above the line 16, is discontinuous, and constitutes a bead-forming upper zone which includes the opposed edge 65 portions 15.

Said discontinuous upper zone is rolled inwardly, to form a discontinuous hollow bead 18, the continuity of which is interrupted by said crevice, the edge portions 15 forming the opposed ends of the bead. The 70 width of the bead-forming zone is such that the bead is entirely above the joint formed by the portions 12 and 13. The bead 18 is therefore composed of a single thickness of sheet metal from end to end, and, owing to 75 the fact that it is entirely above the hoop joint, is adapted to be easily produced by suitable bead-forming appliances, after the joint is formed, there being no contact of any of the portions of the strip from which 80 the bead is formed, with the joint portion of the hoop, and, therefore, no greater resistance to the formation of the bead at the joint portion of the hoop than elsewhere.

The lower zone of the hoop, below the 85 dotted line 16, is formed to bear on the body 20, and on the margin of the cover 21 of a receptacle, such as a butter tub, and is provided with holes 22, to receive attaching nails 23. The bead 18 is formed to bear as 90 a downhold, on the marginal portion of the cover. The heads of the nails 23 may be formed to be engaged and withdrawn by a pulling device, to permit the removal of the 95 hoop and cover.

100 It is obvious, that the hoop, when in the condition shown by Fig. 1, may be beaded by a progressive operation, commencing and ending at the edges 15, the beading operation being easily performed, owing to the 105 fact that the ends of the hoop have been previously secured together.

I claim:

110 A hoop adapted to embrace the upper end of the periphery of a circular receptacle and

secure a cover thereto, said hoop being formed from an elongated sheet metal strip having overlapping joint-forming portions 13 at its opposite ends, said portions overlapping and being united to form a joint which is narrower than the maximum width of the strip, so that the hoop has a continuous receptacle-embracing lower zone including said joint, and a bead-forming upper

zone, the continuity of which is interrupted 10 by a crevice above the joint, said upper zone being rolled inward after the formation of said joint to form a cover-securing bead, located entirely above said joint.

In testimony whereof I have affixed my 15 signature.

GEORGE H. BLISS.
